By his Attorney

H. R. Kerslake.

UNITED STATES PATENT OFFICE.

AUGUSTO NERY PLATERO, OF MONTEVIDEO, URUGUAY.

COLLAPSIBLE HOLDER FOR SHARP-EDGED BLADES OR INSTRUMENTS.

1,373,758.

Specification of Letters Patent. Patented Apr. 5, 1921.

Application filed September 4, 1919. Serial No. 321,697.

To all whom it may concern:

Be it known that I, AUGUSTO NERY PLATERO, citizen of the Republic of Uruguay, residing at No. 1563 Calle Solis, Montevideo, Uruguay, have invented certain new and useful Improvements in Collapsible Holders for Sharp-Edged Blades or Instruments, of which the following is a specification.

10 The present invention relates to "improvements in collapsible holders for sharp edged blades or instruments" its end being that of providing a collapsible holder for sharp edged blades or instruments which, due to 15 its construction, allows the replacement or change of said blades or instruments in a quick and safe manner, permitting its handle and pressing piece to take the place of a box or cover once the holder is shut.

20 In order that my invention may be clearly understood, I represent it in the accompanying drawings in which—

Figure I is a front view of my holder with its parts opened and showing the arrangements in detail.

Fig. II is a front view of the same holder shut.

Figs. III, IV and V are end views taken from one of the extremities of the holder.

30 In Fig. I, *e* and *e'* are two sheets made of metal or any other suitable material as are all the other parts of my holder, which carry the sharp edged blades or instruments. The sheet *e'* is not shown in detail in the accompanying drawings as same goes placed behind sheet *e*. Sheets *e* and *e'* are of identical shape and size. The sheet *e'* carries in its internal face some knobs *d* which fit exactly in some holes *c* of sheet *e*, as shown in the drawings. The sharp blades or instruments which are used with my holder and are placed between the two sheets *e* and *e'* carry in identical position and distance, holes exactly as those *c* of sheet *e*, so that when the blades or instruments are placed between said two sheets *e* and *e'*, the holes correspond exactly and allow the passage of knobs *d* of sheet *e'*. In this way sheets *e* and *e'* and the sharp edged blade or instrument are made secure preventing any vertical movement. The position of sheets *e* and *e'* are more clearly represented in Fig. III which shows said sheets in end view, separated, without carrying the sharp edged blade or instrument in between.

55 Near one of the extremities of sheets *e*

and *e'* is secured by means of a pin, screw or rivet, but with free movement, a U-shaped piece *f* which straddles the upper part of the sheets *e* and *e'* as shown in the drawings. This U-shaped piece *f* on being straddled over the two sheets *e* and *e'*, as shown in Fig. II, presses said sheets and the blade or instrument in between so that the combination forms a solid whole which prevents any movement of the blade or instrument and besides, said U-shaped piece *f* serves as the lid of the box or cover of the collapsible holder. In the same section of the sheets *e* and *e'* but nearer the extremity, there is also secured by means of a pin, screw or rivet, with free movement, another U-shaped piece *g* which serves as a handle as well as the lower part of the box or cover of my holder when same is shut, as it appears in Fig. I (partly opened) and in Fig. II (shut).

Fig. II shows my holder shut, with piece *f* straddled over the sheets *e* and *e'* which carry the sharp edged blade or instrument, and the handle-piece *g* shut.

Fig. III is an end view of the sheets *e* and *e'* separated, showing the position of the holes *c* and knobs *d*.

Figs. IV and V show the same sheets *e* and *e'* pressed by the U-shaped pieces *f* and *g*.

The manner in which my collapsible holder of sharp edged blades or instruments is set up, is as follows: The different pieces of my holder being opened, the sharp edged blade or instrument to be used is placed in between sheets *e* and *e'*, so that its holes correspond to those of sheet *e*, inserting in same the knobs *d* of sheet *e'*; this done U-shaped piece *f* is straddled over said sheets *e* and *e'* and blade therein, thus forming a solid whole which prevents any movement to its parts. The handle-piece *g* is then opened to its limit, which is a horizontal line with sheets *e* and *e'* and my holder is ready for use. When it has been used the handle-piece *g* is shut until it straddles the lower part of sheets *e* and *e'* and the blade or instrument therein thus forming the lower cover of the box of the holder.

Having thus described the nature of my invention and the manner in which same is to be carried into practice, what I claim as my exclusive property and use is:

1. A device for holding and protecting a double-edged blade comprising parallel metal base plates secured together at one

end only, one of said plates being provided with a plurality of apertures, a plurality of pins provided on the other section designed to engage a blade and adapted to enter said apertures, a first cover plate of U-shaped cross-section having parallel side portions pivotally connected to the base plates, designed to engage said base plates for holding the same together, and adapted to protect one edge of a blade held by the base plates and a second cover plate pivotally connected to the base plates and movable into alignment with said base plates to form a handle, the second cover plate being also movable into substantially parallel relation to the base plates for protecting the other edge of the blade.

2. A device for holding and protecting a

double-edged blade comprising a clamp adapted to hold a double-edged blade, a first cover member pivotally connected to said clamp, holding the same in locked position and adapted to protect one edge of a blade carried by said clamp and a second cover member pivotally connected to the clamp and movable into positions in alignment with and parallel to said clamps for forming a handle for the clamps and a protector for the other edge of the blade.

In testimony whereof I affix my signature in presence of two witnesses.

AUGUSTO NERY PLATERO.

Witnesses:

ALFREDO BAL,
GEORGE R. VITAY.
